LAWN EDGING STRIP

Michael T. Tabone, 24881 Ward St.,
Taylor, Mich. 48180

Filed May 8, 1972, Ser. No. 551,558

Term of patent 14 years

Int. Cl. D11—02

U.S. Cl. D35—1

Fig. 1

Fig. 2

Fig. 3

Fig. 4

FIG. 1 is a top plan view of a lawn edging strip showing my new design;

FIG. 2 is a side elevation taken in the direction of line 2—2 of FIG. 1;

FIG. 3 is an end elevation taken in the direction of line 3—3 of FIG. 1;

FIG. 4 is an end elevation taken in the direction of line 4—4 of FIG. 1;

FIG. 5 is a view taken in the direction of line 5—5 of FIG. 3;

FIG. 6 is a view taken in the direction of line 6—6 of FIG. 5; and

FIG. 7 is a cross-section taken along line 7—7 of FIG. 1.

I claim:

The ornamental design for a lawn edging strip, as shown.
